BEDSIDE TABLE

Eugene E. La Vigne, Creve Coeur, Mo., assignor to
Brunswick Corporation, a corporation of Delaware
Filed Apr. 9, 1962, Ser. No. 185,923
4 Claims. (Cl. 108—136)

The present invention relates to bedside tables and more particularly to a bedside table which may be raised and lowered wherein the raising and lowering of the table is aided by a spring means connected between the table top and a base of the table.

Bedside tables which may be raised and lowered have been utilized in hospitals and similar situations in which it is desirable to have a table which may be utilized by a person in bed. Such bedside tables have been conventionally constructed of a base having an upright structure at one end, a table top with a supporting structure at one end thereof which co-operates with the upright portion of the base to support the table top, and a spring means which aids or accomplishes the raising of the table top connected between the top and the base. All of the upright structure of the conventional bedside table is usually at one end for the purpose of allowing the table to be placed across a portion of a bed such as a conventional hospital bed. While the conventional hospital bedside tables presently in use are useful hospital equipment, they have two undesirable features which sometimes create problems in their use. First, the spring means used in conventional bedside tables supplies a varying force to balance the weight of the table top as it extends and contracts with the raising and lowering of the table top. Secondly, when a conventional bedside table is used with an electrically powered hospital bed, the bed is often raised while the bedside table is still placed across it and the bed runs into the table, thereby upsetting it, or squeezes a patient in the bed between the bed and the bottom of the table as the bed rises. The present invention overcomes the first of these prior disadvantages by having a constant force tending to lift and thereby offset the force of gravity on the table throughout its range of vertical positions. The present invention also overcomes the problem of raising a hospital bed toward the underside of a hospital bedside table by having the table rise whenever a small force is applied to its underside.

It is, therefore, an object of the present invention to provide a new and improved bedside table.

Another object of the present invention is to provide a bedside table wherein the table top experiences a constant force opposing the force of gravity upon it throughout its vertical positioning range.

A further object of the present invention is to provide a bedside table wherein the table top experiences a constant upward force supplied by a constant force spring connected between the top and the base of the table.

An additional object is to provide a bedside table having a constant force spring means opposing the force of gravity upon its movable top and a frictional force brake means slightly exceeding the resultant force of the spring and gravity forces.

Yet another object of the present invention is to provide a new and improved locking means for locking the table top throughout a range of vertical positions to the table base.

It is the principal object of the present invention to provide a bedside table having spring means opposing the force of gravity upon its top, a locking means to lock its top position relative to its base, and a handle protruding from the underside of the table top to release the locking means and thereby allow the table top to rise

2

whenever a small force is applied to the bottom of the table top.

A still further object of the present invention is to provide a bedside table having a spring means tending to raise the table top relative to its base and a locking means for holding the table at any vertical position relative to the table base wherein the spring means and the locking means are completely encased within a supporting portion of the table top.

10 Further objects and advantages will become apparent from the following detailed description taken in connection with the accompanying drawings, in which:

FIG. 1 is a perspective view of an embodiment of the present invention;

15 FIG. 2 is a sectional view of a portion of the embodiment shown in FIG. 1 taken along the line 2—2;

FIG. 3 is a perspective view of a portion of the embodiment shown in FIG. 1 with the table top including an encasing cover portion thereof removed;

20 FIG. 4 is a perspective view of another portion of the embodiment of the invention shown in FIG. 1 with the table top removed and the encasing cover and box beams broken away; and

25 FIG. 5 is a sectional elevational view of a portion of the embodiment of the invention shown in FIG. 1 taken along the line 5—5.

While this invention is susceptible of embodiment in many different forms, there is shown in the drawings and will herein be described in detail an embodiment of the invention with the understanding that the present disclosure is to be considered as an exemplification of the principles of the invention and is not intended to limit the invention to the embodiment illustrated. The scope of the invention will be pointed out in the appended claims.

35 As will presently be described in greater detail, the present invention provides for the upward forcing of a top of a bedside table by a constant force regardless of the vertical relationship between the table top and its base. Thus, the possibility of having objects knocked off a table top or thrown in the face of a patient or operator is greatly reduced because the table operator will experience a constant force as he moves the table up or down. Although in the past methods have been devised to reduce the effect of spring rate or a change of force with position, these attempts have never produced a bedside table wherein a force tending to force the table top upward was constant regardless of position.

30 The present invention provides an additional advancement in the art in that the use of a constant force spring in such a bedside table makes it possible to adjust the value of the constant spring force to a value that equals the force of gravity on only the table top or on the table top plus a normal load. In the past, it has not been possible to have a hospital table top remain stationary without providing a locking mechanism. The present invention utilizes the balancing of the force of gravity on the table top or, if preferred, on the table top and a normal load to provide a resulting force upon the table top which is small and easily overcome by a small frictional force. This small frictional force acts to overcome the resultant force of the spring and gravity forces regardless of which force exceeds the other. In this manner, the present invention makes it possible for a table top to move either upward or downward by a light pressure from either a child or a weak adult patient.

35 In the past, many bedside tables have had unlatching handles for the locking means utilized therewith which would be convenient to both a patient in bed or an operator standing beside the table and bed, but these handles were not effective when a hospital bed was inadvertently raised until the bed or the patient engaged the bottom side

of the table as the bed moved upwardly. As will also presently be described in greater detail, the present invention so places the operating handle that it is not only convenient to a patient or operator, but it will automatically be operated to unlock the locking device and allow the table to be raised under a small upward force whenever the operator or patient forgets and the bed or patient is driven upward toward the underside of the table top.

Referring now to FIG. 1, a bedside table is composed of a base generally indicated at 10 and a table top generally indicated at 11. The base 10 is composed of a beam member 12, cross members 13 and 14, casters 15 attached to each end of the cross members 13 and 14 to allow the base to be easily rolled over a floor surface, and a vertical guide portion which, as will presently be described, is enclosed by an enclosure 16 which acts as a supporting portion of the table top 11. Besides the supporting portion 16, the table top 11 is composed of a horizontal platform 17 rigidly secured to the top of the support portion 16.

Referring now to FIGS. 2 through 5 and particularly to FIG. 2, a box shaped member 20 is secured to the beam 12 of the base 10 by a set of bolts and nuts 21. A pair of upright box beams 22 and 23 are welded to the box shaped member 20 and serve as guides for the table top as it is varied in vertical height. These box beams 22 and 23 have their top ends positioned relative to each other by a cross beam 24 rigidly secured to them as shown in FIG. 3. The supporting portion 16 of the table top 11 comprises a rectangular box structure which completely envelopes the box beams 22 and 23 when the table top 11 is in its lowest position as illustrated in FIGS. 1, 2 and 4. The support portion 16 of the table top is spaced from the box beams 22 and 23 by rollers 25 through 28 and a set of nylon spacers 29. The lower rollers 25 and 26 are secured to a rectangular member 30 by mounting bolts and nuts 31 and 32, respectively. The rectangular member 30 is welded to the support portion 16 and supports the rollers 25 and 26 for rolling engagement against a track portion 33 and a track portion 34 of the box beams 22 and 23, respectively, as illustrated in FIGS. 2, 4 and 5. The rollers 27 and 28 are rotationally secured to the top of the box beams 22 and 23 as illustrated in FIGS. 3 and 5 to roll against the inner wall of the support portion 16. The rollers are preferably of the nylon covered steel ball bearing type although they may be of any type well-known in the art. The nylon spacers 29 prevent any metal-to-metal contact between the box beams 22 and 23 and the support portion 16 of the table top 11. Since the weight of the table top 11 and objects placed thereon will tend to bend the table top clockwise as viewed in FIG. 1, pressure will be applied to maintain the respective rollers against both the flanges 33 and 34 and against the interior wall of the support portion 16. Although the friction encountered in these bearings is normally considered quite small, sufficient friction for retarding the rolling of the rollers is created so that it is not overcome by the resultant force of the spring and gravity forces acting on the table top. Thus, the table top will not move up or down until at least a small additional force is applied. The frictional force is usually less than ten pounds, but is sufficient to overcome the difference between the spring and gravity forces acting on the table since their resultant force is usually of the order of less than a few pounds. Therefore, even if there were no latching mechanism provided with the table, the table would remain stationary or could be moved upward or downward with only a light pressure from a child or a weak adult patient.

Thus far, the means for maintaining the table top platform 17 horizontal have been described. The means for applying force to lift the platform 17 and to lock the platform 17 at any desired elevation will now be described in detail. Two coil springs of flexible resilient

metal ribbons 40 and 41 are wound on the drums 42 and 43, respectively, which are rotatably mounted on the cross member 24 by shafts 44 and 45, respectively. The internal ends of the metal ribbons 40 and 41 may be secured to the respective drums 42 and 43 or merely freely wound thereon and the external ends of the ribbons are secured to the rectangular member 30 by a bolt and nut 46. As the external ends of the coils of resilient metal are drawn away from the respective drums, the ribbons are straightened out as shown in FIGS. 3 and 4 with a portion between the straightened part of each ribbon and its part remaining wound on the drum which curves away from the drum as indicated at 47 and 48 in FIG. 3. In these portions of the metal ribbons, the straightening action is occurring and producing the spring force which tends to pull the external end of the spring back into the coil. Regardless of the length of the straight portions of the ribbons 40 and 41, the curved portions 47 and 48 remain substantially the same length. Thus, the spring force acting to pull the rectangular member 30 upward toward the cross bar 24 remains the same regardless of the distance of the rectangular member 30 from the drums 42 and 43. Since the two flexible metal ribbons 40 and 41 are placed back-to-back, their respective positions aid in keeping the portions of the ribbons curving away from the drums equal at all times. The coils of resilient metal ribbons 40 and 41 and their drums 42 and 43 constitute a constant force spring which applies a constant force tending to pull the rectangular member 30 and, therefore, the entire table top 11 upward. No matter where the platform is, in relationship to the base, the force tending to force it upward is constant and an operator or patient need not fear that the force on the platform 17 of the table will change from one elevational position to another. In addition, when the spring force and gravity are closely balanced and a small frictional force is used to overcome the resultant force of the spring and gravity forces, the operator or patient is assured that the resultant force will not vary with the elevation of the table top and, therefore, will not exceed the frictional force at any point throughout its range. Although two springs having separate drums are shown in the figures, it will be easily understood by those skilled in the art that a single spring and drum could be utilized or multiple springs could be substituted or even a multiplicity of springs could be placed alongside each other and wound around a single drum. Thus, the constant force spring means includes either the usage of single or multiple springs in combination with single or multiple drums.

Having now described the constant force spring means which tends to force the platform 17 upwardly at all times, the means for locking the platform at any predetermined elevation within this range will now be described. A shaft 50 has its lower end pivotally mounted in an aperture 51 of the box beam 23 and the box shaped member 20. A pair of cotter pins 52 and 53 position the end of the shaft 50 in the aperture 51 as shown in FIG. 2. The shaft 50 is guided as the table top 11 is raised and lowered in apertures 54 and 55 of brackets 56 and 57, respectively, which are secured to the support portion 16 of the table top 11 by a rivet 58. The guide bracket 56 is welded to the guide bracket 57. A floating wedge plate 60 is positioned between a pair of abutments 59 and 61 and has an aperture 62 which surrounds the shaft 50 so that the wedge plate 60 will lock the shaft 50 to the support section 16 when the wedge plate is pivoted clockwise on 61 out of a horizontal position until it tightly locks the shaft 50. The abutment 59 prevents the floating wedge plate 60 from being pivoted counter-clockwise out of the horizontal position. If this counter-clockwise rotation were not prevented, rotation of a floating wedge plate in either direction would result in locking the wedge plate 60 to the shaft 50. The abutments 59 and 61 are rigidly secured to guide bracket 57. The force for creating the pivotal motion which lock-

the portion 16 to the shaft 50 is supplied by a tension spring 63 which has one end connected to the guide bracket 57 and the other end connected to an end of a shaft 67 which passes through an aperture 64 in the wedge plate 60. If the weight of the table top and its load should ever greatly exceed the spring force, abutment 59 will engage plate 60 to prevent any appreciable downward movement of the table top. A control linkage for operating the wedge plate 60 consists of a rotatable shaft 65, an arm 66 rigidly affixed thereto, and the shaft 67 which is pivotally connected through the aperture 68 in one end of the arm 66 and at its other end to the wedge plate 60 through the aperture 64. A pair of locking handles 69 and 70 are rigidly secured to the shaft 65 by being constructed as extensions thereof. The upward movement of either handle 69 or 70 will rotate the wedge plate about its pivot on 61 against the force of the tension spring 63 to unlock the support portion 16 from the shaft 50. Then the table can be easily raised or lowered since the weight of the table and a normal load of objects placed thereon are balanced by the constant force springs. Thus, it may be seen that anything approaching from below the table will first strike either handle 69 or the handle 70, forcing it upward since these handles project below the bottom of the platform 17 of the table top 11. The upward movement of either handle rotates the shaft 65 and the arm 68 to raise the shaft 67 and thereby pivot the wedge plate toward a horizontal position, unlocking it from the shaft 50. The table top 11 is then free to rise under the influence of any small upward force. With the spring force approximately balancing the force of gravity upon the table top and an expected load and a small frictional force applied to overcome the resultant force even though a few pounds may be added and removed from the table top from time to time, the means for locking the platform would not ordinarily be required. However, this means for locking the platform does act as a safety mechanism in case a severe force should be applied to the top of the table.

In certain specialized applications, it might be desirable to have the ability of the table to remain stationary, dependent upon the locking mechanism being in an engaged position. For such applications, the spring force should be made sufficiently larger or smaller than the force of gravity so that the resultant force will at all times exceed any frictional forces produced between the table top and the base.

As shown in FIG. 1, the handles are conveniently placed to be operated either by a patient in bed or by an operator standing beside the bed. Further, these handles are so placed that the person operating them to move the table can place his hand around the edge of the platform 17 and release the handle simultaneously, making it possible to raise and lower the table, using only one hand. For convenience, a drawer 71 is provided in the platform 17 of the table top 11.

I claim:

1. A bedside table comprising: a base having a vertical guide portion; a table top having a support portion adapted to cooperate with said vertical guide portion of the base to maintain the top horizontal as its vertical position is varied over a range; a constant force spring connected between said base and said table top to apply a

constant force tending to raise said table top over said range; and locking means adapted to operate between said base and said table top to lock said table top at any vertical position within said range and including a vertical shaft secured to said base, a floating wedge plate pivotally mounted between two abutments secured to said support portion of the top, said floating wedge plate having an aperture therein to surround said shaft and to lock said support portion to said shaft by a wedging action when said plate is pivoted from a horizontal position, a spring connected to said wedge plate and to said support portion to force said wedge plate to pivot away from a horizontal position into a wedging lock position with said shaft, and linkage connected to said wedge plate to unlock said wedge plate from said shaft, said linkage including an operating handle rotationally secured to said table top for upward unlocking movement and protruding below the underside of said table top.

2. A bedside table comprising: a base having a vertical guide portion; a table top having a support portion with the top extending laterally from said support portion whereby the top may overlie a bed, said support portion being mounted on said guide portion to maintain the top horizontal as its vertical position is varied over a range; a constant force coil spring connected between said base and the table top, said constant force spring having a plurality of convolutions in overlapping engagement and a straight length extending from the coil with the spring providing substantially the same balancing force in all positions of said table top due to the force being created by the resilience of that portion of the spring which curves away from the coil and extends to said straight portion with said curved portion being substantially uniform in all positions of the table top; locking means for locking said table top to said base in any position of vertical adjustment; and means for releasing said locking means to unlock said top from said base including an operating handle movably mounted on said top and having a length extending beneath and lengthwise of said top.

3. A bedside table as specified in claim 2 including frictional force brake means operating between said base and table top and comprising a set of rollers.

4. A bedside table as specified in claim 2 including frictional force brake means operating between the base and table top and exerting a frictional force of less than ten pounds upon said table top.
